UNITED STATES PATENT OFFICE.

REUBEN HENRY SINK, OF GRASS VALLEY, AND ISAAC POLLOCK, OF REDWOOD CITY, CALIFORNIA.

LAMP-SHADE SUPPORT.

SPECIFICATION forming part of Letters Patent No. 363,916, dated May 31, 1887.

Application filed December 28, 1886. Serial No. 222,775. (No model.)

To all whom it may concern:

Be it known that we, REUBEN HENRY SINK and ISAAC POLLOCK, citizens of the United States, residing, respectively, at Grass Valley and Redwood City, in the counties of Nevada and San Mateo and State of California, have invented a new and useful Improvement in Lamp-Shades, of which the following is a specification.

10 Our invention relates to improvements in lamp-shades; and it consists in certain novel features, hereinafter described and claimed.

Our invention is fully illustrated in the accompanying drawings, in which—

15 Figure 1 is a perspective view of a portion of a lamp with our improved shade attached thereto. Fig. 2 is a top plan view of the same. Fig. 3 is a vertical section in detail of the spring-adjusting device on line $x x$ of Fig. 2. 20 Fig. 4 is a detail perspective view of the spring-adjusting device.

25 Referring to the drawings, in which similar letters denote corresponding parts in all the figures, A is a chimney, and B the collar, of a lamp.

C is a band of sheet metal adapted to encircle the collar B, the ends of which band are free and bent outwardly to form flanges D D'. The arm D' is provided with a threaded opening, d' , and the arm D has a plain opening, d , larger than d' .

30 E is a thumb-screw, which passes loosely through the opening d and screws into the opening d' , thereby making the band adjustable to any lamp-fount.

35 F is a supporting-rod, comprising the long vertical arm G, which is flattened, as shown, for a purpose hereinafter explained, the horizontal arm H, and the short arm I, at right angles to the arm H. Said arm I is also flattened, or made rectangular in cross-section, to enter the oblong loop or sleeve K on the band C. This rectangular construction is designed to prevent the arm I from turning in the sleeve 40 or loop K, but allows endwise movement.

45 K' is a loop or sleeve similar to K, attached to the band C at a point diametrically opposite to loop K.

50 L designates a semi-cylindrical shade of any suitable light material, and provided upon its front side with the metallic adjusting-bracket

M. Said adjusting-bracket M is formed of one piece of sheet metal, having the box N rectangular in cross-section, and ears or flanges O, provided with openings to allow of the insertion of pins or rivets p to secure said adjusting-bracket M firmly to the shade L. The angles $r r$ of the box N are split, as shown, for a considerable distance in from the upper and lower ends of the box N, and the tongues of 55 metal between said split angles are turned in toward the shade to form the spring-tongues S S'—one at the top and the other at the bottom of the box N. The projecting corners T T' at the upper and lower ends of the box N remaining after the tongues S S' are turned in are then pressed laterally toward each other, to prevent the spring-tongues S from coming back to their original positions, thereby limiting their movement. The long flat vertical 60 arm G of the shade-holder is then inserted under the spring-tongues S S'—namely, between said springs and the shade L—and the pressure of the said springs S S' being toward the shade L, the shade will be held at any desired height along the vertical rod G by the pressure of said spring-tongues S S' against and upon the said rod G.

65 The springs automatically hold the shade in its adjusted positions, for as soon as the operator ceases to move the shade the tongue-springs bite against the bar G and hold the shade in the position set. It will thus be seen that we have an easily-applied shade which is adjustable to any height desired. When the 70 shade is not needed, it is only necessary to withdraw the short arm I from the loop K and allow the collar C to remain around the collar B of lamp-chimney.

75 We have shown and described a semi-cylindrical shade; but it will be readily understood that a shade of any form may be employed; also, the specific means shown for securing the rod to the lamp-fount may be varied, as our invention consists in the means employed 80 for holding the shade on the supporting-rod.

85 It will be seen that our shade is so constructed that we can detach the parts thereof to facilitate the packing or transportation thereof, which is an advantage over shades 90 now in general use.

Having thus described our invention, what

we claim, and desire to secure by Letters Patent of the United States, is—

1. The combination, with the collar or band secured to the lamp-fount, and the supporting-rod attached to said band and having the vertical arm G, of the shade having a bracket on its front to receive the said arm G, said bracket being provided with integral spring-tongues which exert a constant tension against the arm G and automatically hold the shade thereon, substantially as set forth.

2. The combination of the supporting-rod provided with means for securing it to the lamp, the shade, and a bracket secured to the shade and provided at its ends with integral spring-tongues projecting in opposite directions to bind against the supporting-rod, substantially as set forth.

3. The combination, with the band C, and

the supporting-rod F, attached thereto, and having the vertical arm G, of the shade L, having the bracket M on its front side to receive the arm G, said bracket being provided with integral spring-tongues to hold the same on said arm G, and limiting-ears to hold the springs to said arms, substantially as specified.

In testimony that we claim the foregoing as our own we have hereto affixed our signatures in presence of two witnesses.

REUBEN HENRY SINK.
ISAAC POLLOCK.
